US00D743400S

(12) **United States Design Patent**
Takahashi et al.

(10) **Patent No.:** US D743,400 S
(45) **Date of Patent:** ** Nov. 17, 2015

(54) **INFORMATION STORAGE DEVICE**(71) Applicants: **Masaki Takahashi**, Kanagawa (JP);
Kunihiro Ohyama, Tokyo (JP)(72) Inventors: **Masaki Takahashi**, Kanagawa (JP);
Kunihiro Ohyama, Tokyo (JP)(73) Assignee: **RICOH COMPANY, LTD.**, Tokyo (JP)(**) Term: **14 Years**(21) Appl. No.: **29/501,858**(22) Filed: **Sep. 9, 2014****Related U.S. Application Data**

(60) Continuation of application No. 13/856,918, filed on Apr. 4, 2013, now Pat. No. 8,909,071, which is a division of application No. 13/691,023, filed on Nov. 30, 2012, now Pat. No. 8,660,441, which is a continuation of application No. 13/448,987, filed on Apr. 17, 2012, now Pat. No. 8,346,105, which is a continuation of application No. PCT/JP2011/063993, filed on Jun. 13, 2011.
